ELECTRIC LOOM

James Lee Young, Jr., Dallas, Tex.

Application May 27, 1937, Serial No. 144,971

5 Claims. (CL. 139—1)

This invention relates to an electric loom, and has for an object to provide a construction wherein all parts of the loom are operated electrically in proper time relation.

5 Another object of the invention is to provide a loom wherein the individual moving parts are provided with individual prime movers which actuate the various parts to cause them to function in the desired way.

10 An additional object of the invention is to provide an improved electric loom using an electric eye as part of the structure for controlling the action of the shuttle.

15 A further object of the invention is to produce a loom electrically operated throughout in a way whereby it will operate at a very high speed and with comparatively high efficiency.

In the accompanying drawings:

20 Fig. 1 is a longitudinal vertical sectional view through the loom disclosing an embodiment of the invention, certain parts being eliminated in the interest of clearness;

25 Fig. 2 is a longitudinal vertical sectional view through a shuttle, part of the lay and associated parts disclosing certain features of the invention;

Fig. 3 is a top plan view of the structure shown in Fig. 2 with the lay eliminated;

Fig. 4 is a side view of the shuttle shown in 30 Fig. 3;

Fig. 5 is an end view of the shuttle shown in Fig. 4;

Fig. 6 is a diagram showing the circuits of the various parts at one end of the loom;

35 Fig. 7 is a diagram showing the circuits of the reed beat-up mechanism and the bobbin-change motion;

Fig. 8 is a diagram showing the warp stop motion and also the filling stop motion;

40 Fig. 9 is an elevation of a harness control mechanism;

Fig. 10 is an end view of the structure shown in Fig. 9;

45 Fig. 11 is a view principally in diagram showing how the structure illustrated in Figs. 9 and 10 actuates the harness;

Fig. 12 is a view somewhat similar to Fig. 6 but showing a modified form of the invention.

Referring to the accompanying drawings by numerals, 1 indicates a frame of a loom which may be of any desired kind and provided with suitable parts for supporting the various moving and stationary parts of the loom. Any desired form of warp beam 2 is provided from which 50 the warp threads 3 and 4 extend and which with

the filling threads eventually form the woven fabric 5 which is wound on the roller 6 carried by swinging arms 7. Preferably there is an arm 7 on each side of the machine and a retractile spring 8 connected with each arm so as to urge the roll of cloth 9 toward the guide or feed roller 10. It will be noted from Figs. 1 and 7 that the fabric 5 passes over the guide roller 10 and then over an idler and is wound on the roller 6 by the friction of the wound fabric 9 against the part 5' of fabric 5 passing over roller 10. Roller 10 is provided with a gear wheel 12 which continually meshes with a pinion 13 rigidly connected with the ratchet wheel 14 which is carried by shaft 15. A swinging arm 16 is pivotally mounted on shaft 15 and carries a pawl 17 which is adapted to engage the teeth of ratchet wheel 14 for rotating the ratchet wheel. A spring 18 tends to hold the parts in the position shown in Fig. 7. However, whenever the magnet 19 is energized it will attract the armature 20 which is part of lever 16 and swing the same downwardly sufficiently for pawl 17 to rotate the ratchet wheel 14 a distance of one notch. This movement will be transmitted through the pinion 13 and gear 12 to the roller 10 and by friction to the roll of fabric 9. After the actuation of each pick magnet 19 is energized and then deenergized so that the fabric 5 is moved to the right as shown in Fig. 1.

Referring particularly to Figs. 1 and 7 it will be seen that the lay 21 is supported by a carriage 22 at each side of the loom frame 1, and this carriage carries magnetic plungers 23 and 24 which operate in the solenoids 25 and 26. It will also be noted that the lay 21 carries the reed 27 so that after the shuttle has placed the filling in the shed, as hereinafter fully described, the movement of the carriage 22 to the right as shown in Fig. 1 will cause the lay 21 to beat up the filling thread in the desired manner. Current from the main supply of wires 28 and 29 is supplied to the solenoids 25 and 26 as shown in Fig. 7. When the magnet 30 is energized, as hereinafter fully described, the swinging contacts 31 and 32 will be brought into engagement with the stationary contacts 33 and 37, whereupon current will pass from wire 28 through conductor 35 to and through the switch 31, contact 33 and wire 36 to the solenoid 25. From the solenoid 25 current will pass to the contact 37, through switch 32 and through the wire 39 back to the feed wire 29. When the magnet 30 is deprived of current the contact members or switches 31 and 32 will be released and will be automatically moved by the retractile spring contacted therewith so as to 55

engage the stationary contacts 38 and 38', whereupon current will be supplied to the solenoid 26 and the result will be that the lay 21 and associated parts will be moved back to the position shown in Fig. 1. During the actuation of the machine it will be understood that these actions will take place rather rapidly. In operation it may be practical to substitute a retractile spring for solenoid 26.

10 The filling yarn is laid in place by electrically actuated shuttles shown particularly in Figs. 2 to 5 inclusive. It will be understood that on each side of the machine there is provided a stator 40 and associated parts so that the description 15 of one will apply to both. As shown in Fig. 2 the stator 40 is provided with a coil 41 which has a metal casing 42 for the return of flux. This arrangement presents the solenoid through which the shuttle 43 is adapted to move. A brass 20 or other suitable lining 44 is provided in the solenoid to permit a proper smooth passage of the shuttle. As shown in Fig. 2, 45 illustrates an electric eye which may be shifted to any desired place, but is preferably arranged substantially 25 as shown in Fig. 2. The lay 21 is secured by suitable brackets 46 or other means to the casing 42 so as to move therewith. The housing 47 is also secured by screws and brackets or other means to the casing 42 so that all of these parts 30 will move in unison with the carriage 22.

The shuttle 43 is provided with laminated metallic ends 48 and 49, and these metal end members are grooved for receiving the respective windings 50 and 51. Winding 50 is connected by suitable wires 52 and 53 to the contact strips 54 and 55 carried on one side of the shuttle and adapted to be engaged by the respective contact springs 56. Similar bars 57 and 58 are connected by wires 59 and 60 with winding 51. 35 This winding coacts with brushes 56 at the other side of the machine. It is to be understood that the winding 50 will be energized at the same time that the winding 51 is energized. It will also be understood that these windings are in such directions that they will augment each other to give a quick strong pull to the shuttle until the shuttle passes in front of the electric eye 45, whereupon the parts will be deprived of current but the shuttle will continue to move under the action of momentum until it reaches the other side and is stopped in a position similar to that shown in Fig. 2. It will be noted that at each end of the shuttle there is provided a contact bar 61 which engages the respective contacts 62 and 63 for closing a circuit at this point, as hereinafter more fully described. A retarding or binding spring 64 is carried by the casing 42 and presses against the side of the shuttle to retard and stop its movement as it enters the shuttle box 47. However, the parts are so proportioned and the binder spring 64 is so adjusted that the shuttle will stop each time with contact bar 61 engaging contacts 62 and 63. It will also be understood that each time the shuttle passes the eye 45 it will shut off the action of this electric eye and thereby produce certain results, as hereinafter described.

Referring particularly to Fig. 6, the diagram for the actuation of the shuttle 43 and the parts shown in Figs. 7, 9, 10 and 11 is disclosed. The winding 41 of the solenoid is supplied with current through the conductors 65 and 66 which are connected through certain instruments to the power wires 28 and 29. Adjacent the coil 41 in 75 Fig. 6 will be seen a source of light 67 which may

be an ordinary incandescent lamp with its rays directed through a lens, and this light illuminates or shines on the photo-electric cell 68 which controls through the tube 69 the current from the supply wires 28' and 29' whereby the sensitive 5 relay C may be supplied or deprived of current. When the rays of light are broken and the photo-electric cell 68 is non-functioning magnet C is deprived of current and consequently the springs connected with the contacts 70 and 71 will cause 10 these members to swing upwardly whereby member 71 is in engagement with the stationary contact 72 and member 70 is out of engagement with contact 73. When the parts are in the position shown in Fig. 2 they are in the same relative position as shown in Fig. 6 and consequently the contacts 62 and 63 are closing the circuit of the wires 74 and 75. Wire 75 extends downwardly and is permanently connected with the member or swinging contact 70 and also is in permanent 20 engagement with the stationary contact 76. Wire 74 extends upwardly and is permanently connected with the power wire 29 and also permanently connected with the wire 79, which in turn is permanently secured to one end of the swinging contact 80. Coacting with the swinging contact 80 are swinging contacts 81 and 82. All of these contacts are adapted to swing upwardly as shown in Fig. 6 under the action of suitable springs and to swing downwardly under the action of the magnet A when the same is energized. Associated with the magnet A is a magnet B which when functioning holds the swinging contacts 83 and 84 against the stationary contacts 85 and 86. 30

In tracing the circuit for the winding 50 of the shuttle it will be seen that current is taken off of power wire 28 and passes through the conductor 87, swinging contact 83, stationary contact 85, and resistor 88 which may be adjusted if desired to one of the brushes 56. From the other brush 56 current will pass through conductor 91, stationary contact 86, swinging contact 84, and conductor 92 back to the power wire 28. A capacitance or condenser 93 is used between one end of the resistor 88 and wire 91 so that when the current is broken the capacitance or condenser will reduce the current in the magnetized coil to substantially zero. This capacitance contains considerably more inductance than in the magnetized coil. It will therefore be seen that whenever the magnet B is functioning current is supplied to the winding 50 of the shuttle. 40

In tracing the circuit of the solenoid coil 41 it will be seen that current will be supplied by wire 28 to the conductor 89 which is connected through suitable swinging contacts 90 and 90' to wire 65 which is permanently connected with one end of the coil 41. The opposite end of coil 41 is connected with conductor 66 which is permanently connected to one end of the swinging contact 81, which contact is held against the stationary contact 94 when magnet A is energized. Stationary contact 94 is connected through wires 95 and 95' to the supply wire 29. When this circuit is closed the winding 41 will be energized. When the shuttle is arranged as shown in Fig. 6 current will pass from the power wire 28 through conductor 96 to wire 97 and through wire 97' to magnet A. From magnet A the current will pass 70 through wire 98 to the stationary contact 73, through swinging contact 70, wire 99 to and through wire 75, through contact 63, bar 61, contact 62, and wire 74 back to the supply wire 29. Current flowing in this direction will energize 75

magnets A and B and consequently will swing all of the swinging contacts 80, 81 and 82 downwardly. This will close the circuit for the solenoid 41. Current flowing through the magnet B will pass from wire 96 through wire 97 to the winding of magnet B, wire 100 to the wire 98 and downwardly as shown in Fig. 6 to the contact 73, through swinging contact 70, wire 99, stationary contact 76, swinging contact 80, and 0 wire 101 back to the supply wire 29.

When the shuttle 43 starts to move it will break one of the circuits of magnet A by reason of the fact that bar 61 has moved away from contacts 62 and 63. Almost instantly after the bar 61 leaves contacts 62 and 63 the shuttle 43 will pass between light 67 and cell 68 whereby the circuit through magnet C will be opened and whereby magnet A will be deprived of current shortly after contact bar 61 starts to move. However, the magnet B will remain energized due to contact at 80 and 76 until the shuttle moves in front of the light 67, whereupon magnet C will be deenergized. This will deprive magnets A and B of current and consequently the contacts 83 and 5 84 will swing open. When magnet C is deenergized as just described, swinging contact 71 will engage stationary contact 72 and will attempt to close the circuit of magnet D. However, the circuit of magnet D is not closed at this time 0 because of the delayed closing of contact 82 which is still held open by the slow release action of magnet A. This slow release is caused by the opening of magnet C a short time after bar 61 leaves contacts 62 and 63. This delay is desired 5 because it is not desired to operate the shuttle throwing mechanism on the left hand side of the loom while the shuttle is still in the shed on the way toward the left hand end. After the shuttle has reached the left hand end and is again in-bound or moving to the right, then the contact at 71 and 72 of Fig. 6 will take place and magnet D will be energized as contact arms 80, 81 and 82 of the magnet A will be in their upward position and contact will have been made at 82. 5 When magnet D is energized it will in turn close the circuit through wires 102 and 103 by reason of the contact 104 swinging down into engagement with the stationary contact 105. The wires 102 and 103 extend to the magnet 30 as shown in Fig. 7 and will energize this magnet as well as magnet 19. As heretofore described, when magnet 19 is energized the fabric will be taken up. When the magnet 30 is energized the swinging contacts 31 and 32 will swing downwardly 10 to the position shown in Fig. 7, whereby current will be supplied to the solenoid 25 for moving the lay forwardly on the beat-up stroke. As soon as magnet 30 is deenergized the swinging contacts 31 and 32 will move into engagement with contacts 38 and 39 for energizing the solenoid 26 which will move the lay back to a position as shown in Fig. 1. It will be understood that the lay functions upon each pick. It will be noted that the magnet D is energized for only a very short time, namely, during the time the shuttle passes lamp 67. It will therefore be seen that the magnets 19 and 30 will quickly function and then become deenergized. In Fig. 6 the magnet B is a quick release magnet and A is a slow release magnet. If preferred, however, the swinging arm contact 82 may be affixed to magnet B instead of magnet A, in which event B should be a slow release magnet and A should be a quick release magnet.

75 As the loom continues to operate the yarn in

the shuttle will become exhausted and when this occurs the mechanism at the left of Fig. 7 will function to stop the loom for any desired time, usually a few seconds in order that a new bobbin may be inserted. As shown at the left in Fig. 7, each time the shuttle moves to the position shown in Fig. 6 the pivotally mounted notched feeler 106 will move through the slot 107 in the shuttle and strike the yarn. As long as there is sufficient yarn on the bobbin the notches on feeler 106 will prevent the feeler from slipping along the bobbin and the feeler mechanism will be pushed backward compressing the spring 111. When the yarn on the bobbin is almost exhausted, however, there will be no yarn to catch on the feeler and the feeler will slip along the bobbin and will not be pushed back by the lay moving forward but will be pushed sideways through movement of the support 106' along the slide groove 106'', thus causing the contacts 109 and 110 to engage. When the feeler 106 has moved along the slide until the contacts 109 and 110 have engaged, the magnet I will be energized by current from the supply wires 28 and 29. It will be noted that this current passes through the swinging contact 112 which is normally held against the stationary contact 113. It will remain energized after the lay has returned to the backward position (breaking contact at 109 and 110) through the contacts 114 and 116.

When the magnet I has been energized the swinging contacts 114 and 115 will be swung over into engagement with the respective stationary contacts 116 and 117. When this takes place current will pass through wire 118 to the magnet Y shown in Fig. 6 and back through wire 119 to the stationary contact 117 and thence back to the supply wire 29 through the swinging contact 90' shown in Fig. 6 to open the circuit of the solenoid or coil 41 whereby the shuttle will not function. This circuit will remain open as long as magnet I is energized. At the same time that the magnet Y (Fig. 6) is energized the time delay magnet J (Fig. 7) will be energized and will cause the swinging contact 120 to move into engagement with the stationary contact 121. This will close the circuit for magnet K and consequently magnet K will move the swinging contact 112 away from the stationary contact 113 after the delay necessary to operate magnet J. This will deenergize magnet I so that all the circuits will be automatically restored and the loom will start to function again.

During the time that the loom has stopped a new bobbin will have been placed in the shuttle 43. The new bobbin may be placed in the shuttle manually if desired, but as shown in Fig. 13 automatic means have been provided for securing this result. The wires 122 and 123 extend to the magnet M of the bobbin replacing mechanism shown in Fig. 13. It will therefore be seen that this replacing mechanism will function during the time that current is supplied to the magnet Y in Fig. 6. In Fig. 13 there is provided a drum 125 carrying a number of bobbins 126. A lever 127 is pivotally mounted at 128 and is provided at one end with an armature 129 adapted to be attracted by the magnet M. The other end of the lever is provided with an arc-shaped pusher 130 positioned to engage and push one of the bobbins 126 downwardly into the shuttle 43. As the new bobbin is forced into the shuttle 43 the old bobbin is forced downwardly and out of the shuttle. During the downward movement of the lever 127 the pawl 131 moves over the ratchet wheel 132 which 75

- is secured to drum 125, but when the lever is moved upwardly pawl 131 under the action of spring 133 will move the drum 125 a distance equal to the spacing of the bobbins on the drum so that a new bobbin will be ready to be fed into the next empty shuttle. It will be understood that the shuttle is open at the top and bottom and that this part of the shuttle is old and well known and that the practice of forcing the old bobbin out by a new bobbin is old and well known.
- 10 In Fig. 8 stop motion mechanism will be seen. From this figure it will be noted that each of the warp yarns is provided with a contact member 134 which is normally supported by the warp yarn.
- 15 When any of the yarns break the contact 134 carried thereby will drop down and connect the contacts 135 and 136. This will close the circuit of wires 137 and 138 which are connected to the magnet 139 shown in Fig. 6. When the contacts
- 20 135 and 136 are connected magnet 139 will swing the contact 90 out of engagement with its stationary contact for opening the circuit of the coil 41. This circuit will remain open as long as the contacts 135 and 136 are connected. In regard to a stop motion for the filling yarn, a fork 140 is provided which engages the filling yarn 141 and the engaged end will be held down so that the extension 142 will be supported above the hook 143 which is connected with the lay 21. The fork 140 is slidably mounted in a support 144. Fork 140 carries a pin 145 which is pressed by a spring 146. In case the filling yarn 141 is broken the fork 140 is so proportioned and pivoted on pin 145 whereby the curved feeling end will be elevated and the extension 142 will be lowered. When this occurs lay 21 will move to the left as shown in Fig. 8 and the hook 143 will engage extension 142 and move the fork 140 so that the contact 147 will engage the contact 148 and close the circuit of wires 137 and 138, whereby magnet 139 shown in Fig. 6 will be energized and the coil 41 deprived of current. This will stop the functioning of the machine until the filling yarn has been taken care of.
- When the magnet D (Fig. 6) temporarily closes the circuits of wires 102 and 103, magnet G (Fig. 10) will be energized. It will be understood that wires 102 and 103 are connected with magnet G as well as the other devices heretofore described. When magnet G is energized it will attract its armature 149 and swing the arm 150 which is pivotally mounted on the shaft 151. Shaft 151 carries a drum 152 to which is rigidly secured a ratchet wheel 153 coacting with pawl 154 pivotally mounted on lever 150. Whenever the lever 150 is swung downwardly as shown in Fig. 10, ratchet wheel 153 will be moved the distance of one tooth, thus moving drum 152 one step forward. When the magnet G is deenergized spring 155 will quickly move the arm 150 back to the upward position. Drum 152 is provided with a number of metal bars 156 (Fig. 9) grounded on shaft 151. Bars 156 are provided with a number of apertures so as to receive the various metal pins 158. There is provided a metal contact spring 159 for each circumferential row of apertures and all of said springs are supported by metal bar 160 but insulated therefrom by the insulating strip 160'. A conductor 161 (Fig. 11) is connected with supply wire 28 and also with shaft 151. A conductor 162 is connected with supply wire 29 and with one end of the winding of solenoid 163. The other end of the winding of solenoid 163 is connected through wire 164 to the spring contact 159. The solenoid 163 has a plunger 165 which is connected with the harness
166. It will be understood that there may be several frames of the harness 166 and that each frame is connected with a separate plunger 165 and with a spring or weight 167. It will therefore be seen that each contact 159 is in a separate circuit including a solenoid 163 so as to give individual control of each harness frame 166. There may be one frame for each circumferential row of apertures in the drum 152, or if desired there may be only two frames so as to provide for the desired shed during the functioning of the machine.
- It will be understood that whenever any spring 159 is engaging a pin 158 the frame 166 will be elevated and held elevated as long as the spring 15 is in engagement with the pin. When the drum 152 is rotated for one step all of the springs will move to the next bar 156 which may have only a certain number of pins. For instance, if there are only two frames 166 the first row of 20 apertures will be provided with a pin in each alternate opening and the second row will be likewise provided with a pin in each alternate opening, but the pins in the second row will be alternated. In this way one frame 166 will be 25 elevated and the other lowered. The pins could be arranged in other desired ways. By this arrangement the operation of quite a few harnesses may be provided for and also means that dobby weaves could be made at the same speed as plain 30 weaves.
- In the construction shown in Figs. 2 and 6 the movement of the shuttle 43 is caused by the attraction of the coil 41 in connection with the winding 50. However, the parts could be arranged to cause the shuttle to be given a push by the solenoid when the same is part of the way through. An arrangement of this kind is shown in Fig. 12 which, generally speaking, is the same as Fig. 6 but with sufficient modification 40 to secure the results just mentioned. Referring to this figure it will be seen that a magnet E is provided for closing the respective swinging contacts 168 and 169. Also the magnet C is provided with an additional swinging contact 170. The brushes 56 are set sufficiently close to the outside (left side) of the solenoid so that they will contact with contact bars 57 and 58 of the windings 51 of the right hand end of the shuttle just a fraction of a second before the ray of light at 67 is again uninterrupted due to the passing of the extreme right end of the shuttle. By an arrangement of this kind and by having the winding of the magnetic relay E in series with the winding of the secondary on the shuttle, the relay E would be electrified shortly before the sensitive relay C returned to its original position, which it will do as soon as the ray of light is uninterrupted. However, inasmuch as relay E has been electrified then contact has been made 55 at points 168' and 169' which continues to keep the circuit closed even though the sensitive relay C returns to its normal position breaking contact at 170' and 72. On the inbound trip when it would not be desired to operate this mechanism, it would be operated only for a fraction of a second even though the brushes would make contact on the inbound trip. Notwithstanding this fact, the circuit would not be completed until the ray of light was broken 60 and to take care of this condition the length of the contact plates 57 and 58 could be adjusted so that this would only be a fraction of a second before the contact with the brushes is broken. Even if the mechanism operated for this frac- 65
- 70
- 75

tion of a second it would only tend to slow down the motion of the shuttle which is more or less desirable at that point. As shown in Fig. 1 the lay is operated by means of the carriage 22 but if 5 desired this method of actuation could be applied to the ordinary swinging type of lay operated about a pivot near the bottom of the loom without departing from the spirit of the invention.

10 It will also be understood that some of the magnets or solenoids may require lower voltage due to the fact that they be more or less exposed and therefore all magnets may not be operated directly off the power lines 28 and 29. 15 Timing and coordination may be controlled accurately by adjusting the speed of the tripping and releasing of the various magnets and by shifting the electric eye along the route of the shuttle.

20 I claim:

1. A loom for weaving fabric including a lay provided with a reed, a shuttle, electrically actuated means for actuating said lay and reed, and means for actuating said shuttle in time with said 25 lay and reed, said last-mentioned means including an electric eye positioned to have the rays of light broken by said shuttle as said shuttle moves from one extreme position to the other.

2. A loom for weaving fabric comprising a 30 frame, a forwardly and rearwardly reciprocating lay, a reed secured to said lay and moved thereby, electrically actuated solenoids for actuating said lay, a shuttle, and means including an electric eye on each side of said frame for actuating said shuttle, said shuttle interrupting the 35

light to said electric eyes adjacent each end of its travel.

3. A loom for weaving fabric formed with an independent electrically actuated prime mover for each of the moving parts of the loom and means including a photoelectric cell on each side of the loom for timing and co-ordinating said prime movers so that the various moving parts of the loom will operate in proper timed relation to each other. 10

4. A fabric loom for plain and dobby weaves, including a lay provided with a reed, a shuttle, electrically actuated means for actuating said lay and reed, a harness for actuating the warp yarn to form a shed, electrically actuated means 15 for actuating said harness, electrically actuated means for actuating said shuttle, and an electric eye for timing and co-ordinating the electrically actuated means for actuating the lay and reed, the harness, and the shuttle, said electric eye 20 being positioned to have the rays of light broken by said shuttle as the shuttle moves from one extreme position to the other.

5. In a loom, a harness, a solenoid for raising the harness at spaced intervals, a lay and reed, 25 a shuttle, means for actuating said lay and reed, means for actuating said shuttle, and an electric eye on each side of the loom for timing and co-ordinating the action of said solenoid and the action of the means for actuating the shuttle, 30 said electric eye being positioned to have respectively the rays of light broken by said shuttle as the shuttle moves from one extreme position to the other.

JAMES LEE YOUNG, JR. 35
